UNITED STATES PATENT OFFICE.

DOW O. WHELAN, OF SCHENECTADY, NEW YORK, ASSIGNOR TO GENERAL ELECTRIC COMPANY, A CORPORATION OF NEW YORK.

PROTECTIVE APPARATUS.

Application filed May 13, 1925. Serial No. 30,029.

My present invention relates to protective apparatus especially adapted for use in thermionic amplifier systems.

In the operation of thermionic amplifier systems, such for example, as those employed for radio reception, difficulty is sometimes experienced by the accidental impressing of the B-battery voltage across the filament terminals of the thermionic amplifier tubes, 10 resulting in the burning out of the filaments. It sometimes happens also that if a short circuit occurs in the socket whereby the full B battery voltage is impressed upon the transformer coils, these coils may be seriously damaged by reason of the heavy current flowing therein.

The object of my invention is to provide an apparatus for protecting the amplifying apparatus from both of these dangers.

It has been proposed to employ in series with the supply batteries of an amplifying set, a resistance of such value that the maximum current which can flow under short-circuit conditions, or when the full battery 20 voltage is applied to the filament terminals will be too small to cause any damage. This, however, requires the use of different values of resistance in case different potentials are used for different devices, and may also produce a harmful reaction between the circuits of the different devices.

I have found that it is possible to overcome the disadvantages in the previously suggested methods of employing resistances by the use of a resistance which varies in a critical manner with variations in its temperature. Such a resistance may be conveniently of the form of a tungsten filament enclosed in an atmosphere of hydrogen or other inert gas. The resistance of this filament at the normal operating temperature 35 may be comparatively low, but if the current passing through it tends to increase above a certain critical value the resistance will increase very greatly and thus limit the current to some predetermined value which will not damage the apparatus, at the same time giving a visible indication of the short-circuit condition.

I have also found that it is possible to construct a single device which will take care of the requirements of the situation in the case where different voltages are employed for different amplifiers. This may be ac-

complished by providing a contact to some 55 intermediate point in the filament so chosen that a portion of the filament may be connected in series with the devices which are supplied with current at a lower potential while the entire filament is connected in 60 series with the devices which are supplied with a higher operating potential, the signal thus indicating in which circuit the trouble occurs.

The novel features which I believe to be 65 characteristic of my invention are set forth with particularity in the appended claims. My invention itself, however, both as to its organization and method of operation will best be understood by reference to the following description taken in connection with the accompanying drawing in which Fig. 1 shows diagrammatically a manner in which my invention may be carried into effect and Fig. 2 is a view in perspective of a resistance 70 device adapted for use in connection with my invention.

I have indicated diagrammatically in Fig. 1 various potential sources which may be employed in a thermionic amplifier system. 1 represents the "A"-battery employed for supplying heating currents to the tube filaments; 2 represents a 45 volt battery, such as is customarily employed for supplying plate potential to the detector 75 tubes; 3 represents a second 45 volt battery, which may be employed in series with 2 for supplying 90 volts to certain amplifier tubes; 4 represents another 45 volt battery, which may be connected in series with 2 and 3 for 80 supplying 135 volts to a higher power amplifier tube; 5 represents a C battery which may be provided with taps as indicated, for furnishing grid bias to the different tubes.

The protective device 6 has a filament 7, enclosed in an evacuated bulb 8, containing a filling of hydrogen or other non-oxidizing gas. Filament 7 has one terminal connected to the positive terminal of battery 2 and the other terminal to the negative terminal of battery 3 so that the operating current supplied to the amplifier tubes operating at 90 and 135 volts is required to flow through the entire length of the filament. The filament is tapped at an intermediate point 9 and from this tap voltage may be supplied to 95 the detector tubes, so that the current to

these tubes passes through only the portion of the filament between this tap 9 and the positive terminal of the battery 2.

In Fig. 2 I have shown one manner in which the protective device 6 may be constructed. The ends of the filament 7 are connected to leading-in conductors which are sealed into the stem 10 and connected to two terminals which are embedded in the insulating member 11 of the base. One terminal 12 is shown in the drawing. The other terminal is not shown. The whole device may be constructed in a manner similar to that employed for automobile lamps. The intermediate tap 9 to the filament 7 is also connected to a leading-in conductor extending through the stem 10, and this leading-in conductor is connected at 13 to the shell 14 of the base. Contact may be made to the three terminals thus provided by means of any suitable form of socket.

It will be seen that by the arrangement described, if a conductor which is connected to the positive terminal of a plate battery should accidentally come into direct contact with a negative filament terminal, the current which will thus be caused to flow in the filaments will have to pass through the filament 7 of the protective device. By the proper proportion of the filament 7 its resistance may be made to increase to such an extent that the maximum current which will flow through it at the maximum battery potential which may be applied under these circumstances will be too small to burn out the filaments of the tubes. The effective limitation of the current obtained in this way will also be sufficient to prevent any injury to the transformer windings connecting successive amplifying tubes in case of the direct application of the full battery voltage across a transformer winding. In each case the filament will glow thus giving the danger signal which will allow the batteries to be disconnected before they are damaged.

If desired, a similar protective lamp may be employed at the junction between batteries 1 and 2, a portion of the filament being connected to supply and regulate current to the filaments of the tubes while the entire filament is connected in series with the B battery. Other modifications of the manner of using the protective device as well as in the precise form of device employed may be made without departing from the scope of my invention as set forth in the appended claims.

What I claim as new and desire to secure by Letters Patent of the United States, is,—
1. A protective device for an amplifying system having a plurality of thermionic discharge devices and sources of potential of different value for different devices, comprising a resistance which varies in value in a critical manner with the current flowing

therein, said resistance being so connected to the system that the operating current supplied from a source of lower potential is required to flow through a portion only of the resistance, and the operating current supplied from a source of higher potential is required to flow through the entire resistance. 70

2. A protective device for an amplifying system having a plurality of thermionic discharge devices and a plurality of sources of potential adapted to be connected in series to furnish different operating potentials for different devices, comprising a resistance which varies in value in a critical manner with the current flowing therein, said resistance having one terminal connected to the positive terminal of one of said sources, and its other terminal connected to the negative terminal of another of said sources, and a connection to an intermediate point of said resistance for supplying operating current to one of said devices at a lower potential than that of other devices. 80

3. A protective device for an amplifying system having a plurality of thermionic discharge devices and sources of potential of different value for supplying different circuits comprising a resistance which varies in value in a critical manner with the current flowing therein, said resistance being so connected to the system that the operating current supplied from one of said sources is required to flow through a portion only of the resistance and the operating current supplied from another source is required to flow through the entire resistance. 90

4. A protective device for an amplifying system having a plurality of thermionic discharge devices and a plurality of sources of potential for supplying different circuits comprising a resistance which varies in value in a critical manner with the current flowing therein, said resistance having one terminal connected to the positive terminal of one of said sources and its other terminal connected to the negative terminal of another of said sources, and a connection to an intermediate point of said resistance for supplying operating current to one of the circuits of said system. 100

5. A protective device of an amplifying system having a plurality of sources of potential for supplying different circuits comprising a resistance so connected to the system that the operating current supplied to one circuit is required to flow through a portion only of the resistance and the operating current supplied to another circuit is required to flow through the entire resistance, said resistance having a comparatively low value when the normal operating current flows therethrough, but having the property of increasing greatly in value when the current flowing therethrough appreciably exceeds the normal current. 110

6. A protective device for an electrical network comprising a plurality of circuits to which different potentials are supplied comprising a resistance so connected to the system that the operating current supplied to one circuit is required to flow through a portion only of the resistance when the operating current supplied to another circuit is required to flow through the entire resistance, said resistance having a comparatively low value when the normal operating current flows therethrough and having the property of increasing greatly in value when the current flowing therethrough appreciably exceeds the normal current.
7. A protective device for an electrical network having a plurality of circuits adapted to be supplied by different potentials comprising a resistance which varies in value in a critical manner with the current flowing therein, said resistance being so connected to the system that the operating current supplied from a source of lower potential is required to flow through a portion only of the resistance and the operating current supplied from a source of higher potential is required to flow through the entire resistance.

In witness whereof, I have hereunto set my hand this 11th day of May, 1925.

DOW O. WHELAN.
